UNITED STATES PATENT OFFICE.

JOHN CLARK, OF BUFFALO, NEW YORK.

HOISTING HOOK.

Application filed May 28, 1925. Serial No. 33,402.

To all whom it may concern:

Be it known that I, JOHN CLARK, a citizen of the United States, residing at Buffalo, in the county of Erie and State of New York, have invented new and useful Improvements in Hoisting Hooks, of which the following is a specification.

This invention relates to a hoisting hook which is more particularly designed for use 10 in connection with hoisting tackle and machinery which lifts heavy loads from one place to another, such for example as freight, packages and structural material to and from a ship, railway car or wharf.

Hoisting hooks for this purpose as heretofore constructed were liable to become 15 caught against obstructions either while ascending or descending and the same were also liable to release the load or become unlatched therefrom, thereby not only interfering with the progress of transferring the material from one place to another but also endangering the safety of the operatives.

It is the object of this invention to provide a hoisting hook for this purpose which is not only stronger and more durable than those heretofore known but is also not liable to foul against adjacent obstructions and is also incapable of becoming 20 detached from the load and thereby enable freight to be handled with maximum safety to the operatives and also without any delay due to possible interferences.

In the accompanying drawings:—

Figure 1, is a side elevation of a hoisting hook which embodies a satisfactory form of my invention.

Figure 2, is a front elevation of the same.

Figure 3, is a vertical longitudinal section of the same.

Figure 4, is a horizontal section taken on line 4—4, Fig. 1.

Similar characters of reference indicate 45 like parts throughout the several views.

The main part or body of this hoisting hook comprises an upright shank 10 and a forwardly and upwardly turned beak 11 at the lower end of this shank forming an upwardly opening mouth between this shank and beak which is adapted to receive the ring, rope or other means whereby the load to be lifted is attached to the hoisting hook. At its upper end the shank is provided 50 with means whereby the same is connected to the hoisting mechanism. In the present

instance this is accomplished by means of an eye 12 which overhangs forwardly from the upper end of the shank and receives the lowermost link 13 of a hoisting chain 60 forming part of the hoisting tackle or mechanism, such as that now in common use for this purpose.

By overhanging the attaching eye 12 forwardly the center of gravity of the hoisting hook is brought nearly in line with the mouth of the hoisting hook so that the weight of the load suspended by the hoisting hook will be forced to hang to a greater extent from the shank 10 and thereby relieve the beak 11 to a corresponding extent from this load so as to reduce the liability of breaking the latter to a minimum.

For the purpose of still further increasing the strength of the beak, also to prevent accidental disengagement of the load from the mouth of the hoisting hook and also to prevent the hoisting hook from fouling or becoming caught against obstructions, the following means are provided:—

Movable into and out of a position across the mouth of the hoisting hook in a keeper or latch 14 which is preferably permanently connected with the upper part of the shank while its lower end is detachably connected with the beak of the hoisting hook so as to permit of opening and closing the mouth of the same.

At its lower end this keeper or latch is provided with an inwardly projecting hook 15 which in its operative position projects inwardly through an opening 16 in the upper part of the beak.

At its upper end the latch or keeper is connected by means of a swivel joint with the upper part of the beak 10 below the eye 12 thereof so as to permit the keeper to not only swing in a vertical plane parallel with the plane of the shank 10 and beak 11 for the purpose of engaging and disengaging the hook 15 of the keeper with the opening 16 of the beak, but also to permit the keeper to swing vertically in a plane at right angles to the plane of the shank and beak for the purpose of permitting the keeper to completely uncover the mouth of the hoisting hook and permit a ring, rope or other means of attachment on the load to be freely inserted into the mouth of the hoisting hook and also removed therefrom. The preferred form of this swivelling connection

is of such a character that the same may also be utilized for locking the keeper in its operative position, and as shown in the drawings the same is constructed as follows:—

5 At its upper end the keeper is provided with an upwardly projecting foot 17, the inner side of which is adapted to bear against the opposing upper part of the inner side of the shank 10. The upper part of the inner side of this foot is rounded, as shown at 18 and adapted to engage with the adjacent rounded surface 19 on the upper part of the inner side of the shank 10 and thereby permit the keeper to be locked or turned in 15 a vertical plane parallel with the beak 11 and shank 10 for the purpose of engaging and disengaging the hook 15 of the keeper with the opening 16. The foot of the keeper is provided with a vertical slot 20 which receives the central part of a clamping or 20 tightening bolt 21 which latter is connected at its inner end with the adjacent upper part of the shank 10 by means of a screw joint 22, as shown in Figs. 3 and 4. The outer end 25 of the bolt 21 is provided with a screw thread 23, preferably of the acme type which receives a clamping screw nut 24 adapted to engage with the outer side of the foot 17 of the keeper and press the same against the 30 shank 10 for the purpose of holding the keeper across the mouth of the hoisting hook and in an interlocked position with the beak of the same. In order to permit the keeper to rock freely in a vertical plane parallel 35 with the shank 10 and beak 11 upon loosening the clamping bolt 24 only to a moderate extent the co-operating surfaces of the clamping nut 24 and the coupling foot 17 of the keeper are constructed so that a spherical joint or ball joint is formed between the same, this being accomplished by making the inner side 25 of the nut of convex spherical form and the outer side of the foot 17 of concave spherical form, as shown in Figs. 40 3 and 4.

45 Complete detachment of the clamping nut 24 from the clamping and pivot bolt 21 is prevented by means of a stop device which preferably consists of a stop disk 27 arranged on the outer end of the clamping bolt 21 and over-hanging the sides of the same and detachably connected with this bolt by means of a screw 28 or other suitable means. In order to avoid making the 50 clamping bolt 21 unduly long and still permit the clamping nut 24 to be unscrewed as far as necessary to completely release the keeper a recess 29 is formed on the outer side of this nut which receives the stop disk 27 in the outermost position of this nut, as shown by dotted lines in Fig. 3.

55 Turning of the clamping nut 24 may be effected in any suitable manner for instance by nurling the periphery thereof, as shown at 60 30 in Fig. 1 and also by inserting a

wrench pin into one or another of a plurality of wrench openings 31 formed in different parts of the periphery of this screw nut, as shown in Figs. 1, 3 and 4.

When this hoisting hook is in use and 70 the keeper is locked in a position across the mouth of the same the hook 15 of the keeper engages with the opening 16 of the beak 11, the foot 17 of the keeper engages the lower end of its slot 20 with the clamping bolt 21 and the screw nut 24 presses this foot against the upper part of the shank 10, as shown by full lines in Figs. 1 and 3. For the purpose of opening the mouth of the hook in order to permit the load 80 to be detached from the mouth thereof and another load substituted, the screw nut 24 is first loosened by unscrewing the same sufficiently for this purpose after which the keeper may be turned in a vertical plane 85 parallel with the plane of the shank 10 and beak 11. At which time the foot 17 at the upper end of the keeper will slide downwardly between the nut and shank 10 until the upper part of the slot 20 of the 90 foot engages with the top of the clamping bolt 21, thereby releasing the hook 15 of the keeper from the beak 11, as shown by dotted lines in Fig. 3. The keeper may now be swung in a vertical plane at right 95 angles to the plane of the shank and beak of the hoisting hook for the purpose of completely uncovering the mouth of the hoisting hook, this extreme opening position of the keeper being represented by dotted lines in Fig. 1.

Upon reversing the operation of the parts as just described the keeper will be again returned to its working position for closing the mouth of the hoisting hook and confining the load therein. 105

In order to produce a positive upward pull of the shank on the keeper in addition to the frictional pull against the same by means of the clamping bolt and nut an 110 upwardly facing shoulder 32 is formed on the central part of the inner side of the shank 10 which shoulder engages with the adjacent upper part of the surface of the keeper, as shown in Figs. 1 and 3. By this means the upper part of the beak 11 is positively and reliably connected with the upper part of the shank so that the beak is strengthened and re-inforced against 115 breakage under the load and the hoisting hook as a whole is substantially as strong as a completely closed link.

The inner part of the attaching eye 12 of the shank overhangs to a considerable extent the clamping and coupling means 125 whereby the keeper is connected at its upper end with the shank of the hoisting hook, and the keeper and the means for connecting the same with the shank and beak are so constructed that they form a 130

substantially even surface, thereby avoiding any pronounced shoulders on the exterior of the hoisting hook which are liable to be caught on other objects so that the 5 hoisting hook is not liable to be fouled either while loading or unloading freight or similar material and thus expediting work of this character and effecting a corresponding reduction in cost.

10 Inasmuch as the keeper is positively locked across the mouth of the hook when the same is in its tightened or operative position the load which is being transported can not become accidentally detached from 15 the hoisting hook, thereby avoiding possible injury to the operatives who are doing the work.

All of the several parts of this hoisting hook and the means for closing the mouth 20 of the same are permanently connected with each other so that they practically form a complete unit, the several parts of which can not become loose, thereby expediting the work of transferring material by means 25 of this hook and reducing the cost accordingly.

Inasmuch as this hoisting hook is comparatively simple in construction and its several parts are strong and durable and not 30 liable to give way under any load likely to be imposed upon the same, this increases the safety of the operatives in the work of handling freight. Moreover this hoisting hook is capable of use in connection with 35 hoisting apparatus of the usual construction now in general use so that no change need be made therein for receiving the hoisting hook made in accordance with this invention.

40 If the stud bolt 21 should become broken the same can be easily replaced by a new one. In order to compensate for the removal of metal in forming the opening in the shank which receives the stud bolt 21 45 the adjacent sides of the shank are thickened, as shown at 100, thereby strengthening the shank and enabling the same to sustain the maximum load which is likely to be carried by the hoisting hook.

50 Instead of making the bolt 21 in the form of a stud bolt, as shown in the drawings, this bolt may be made in one piece with the shank.

I claim as my invention:—

55 1. A hoisting hook comprising a shank and a beak, and a keeper movable into and out of a position across the mouth of said hook and having one end pivotally connected with said shank so as to be capable of turning 60 in a plane at right angles thereto and adapted to be detachably connected at its opposite end with said beak and said shank being provided on its front side with a

shoulder adapted to engage with the under-side of said keeper.

65

2. A hoisting hook having a shank and a beak provided with an opening, a clamping bolt arranged on the front side of said shank, and a keeper movable into and out of a position across the mouth of said hook 70 and capable of turning on said bolt parallel with the plane of said shank and beak and also sliding lengthwise thereof and provided with a hook adapted to engage with the opening of said beak.

75

3. A hoisting hook comprising a shank and a beak having an opening, a clamping bolt having a body projecting forwardly from the shank, and a keeper movable into and out of a position across the mouth of said hook and provided at one end with a longitudinal slot which receives said bolt body and a hook at its opposite end which is adapted to engage the opening of said beak.

80

4. A hoisting hook comprising a shank and a beak having an opening, a clamping bolt having a body projecting forwardly from the shank, a keeper movable into and out of a position across the mouth of said hook and provided at one end with a longitudinal slot which receives said bolt body and a hook at its opposite end which is adapted to engage the opening of said beak, and a screw nut arranged on said bolt body and engaging with the front side of said keeper.

85

5. A hoisting hook comprising a shank and a beak having an opening, a clamping bolt having a body projecting forwardly from the shank, a keeper movable into and out of a position across the mouth of said hook and provided at one end with a longitudinal slot which receives said bolt body and a hook at its opposite end which is adapted to engage the opening of said beak, a screw nut arranged on said bolt body and engaging with the front side of said keeper, and means for preventing said nut from wholly unscrewing from said bolt body.

95

6. A hoisting hook comprising a shank and a beak having an opening, a clamping bolt having a body projecting forwardly from the shank, a keeper movable into and out of a position across the mouth of said hook and provided at one end with a longitudinal slot which receives said bolt body and a hook at its opposite end which is adapted to engage the opening of said beak, a screw nut arranged on said bolt body and engaging with the front side of said keeper, the rear side of said keeper which engages said shank being rounded, and the co-operating surfaces of said keeper and screw nut being of spherical form.
